UNITED STATES PATENT OFFICE.

GEORG MAYER, OF CHICAGO, ILLINOIS, ASSIGNOR OF ONE-HALF TO CONRAD NEU, OF CHICAGO, ILLINOIS.

COOKING UTENSIL.

1,128,995.

Specification of Letters Patent. Patented Feb. 16, 1915.

Application filed March 9, 1914. Serial No. 828,632.

To all whom it may concern:

Be it known that I, GEORG MAYER, citizen of the United States, residing at Chicago, in the county of Cook and State of Illinois, have invented certain new and useful Improvements in Cooking Utensils, of which the following is a specification.

The essential object of this invention is to provide a utensil particularly intended to be used as an attachment for the receptacle or receptacles in which doughnuts are cooked. As is well known in the art, the cooking of doughnuts involves the use of a body of hot molten lard or grease, and the odors and vapors which arise, particularly when the doughnuts are cooling, is very objectionable.

It is the object of this invention, therefore, to provide an attachment which will carry off the undesirable vapors and yet at the same time not interfere with any of the necessary features of the cooking or cooling of the doughnuts.

In the drawings, Figure 1 is a side elevation of the invention, showing the same superposed above a doughnut-holding receptacle and the stove or other source of heat; Fig. 2 is a view at an angle of 90 degrees to Fig. 1, the stove being removed; Fig. 3 is a detailed view of a part of the hood; and Fig. 4 is a top plan view of the doughnut-holding receptacle.

To the wall 1 the brackets 2 and 3 are secured, said brackets being adapted to project outwardly and to grasp the hood 4, which hood is retained in fixed position above the stove 5. At the top of said hood 4 is a sleeve 5 from which a stove pipe or conduit leads to the flue or chimney of the building (not shown) and the odors or vapors of the cooling doughnuts make their exit through the sleeve 5, being carried out of the room through said sleeve and the pipe and flue which are connected thereto.

Below the hood 4 (which hood is provided with a conical top) is a chamber 6 in the wall of which is cut the arcuate slot 7, and slot 7 should be sufficiently large to permit access and removal of the foraminous retainer 8 within which the doughnuts are placed. The retainer 8 preferably comprises a wire-mesh basket provided with outwardly-projecting handles 9 which are conveniently in L-shaped form, having ends

which project out beyond the wall of chamber 6. Above the opening 7 the wall of the chamber 6 is slotted at 10 and catches or locking dogs 11 are pivoted at 12 to the wall of chamber 6 adjacent to said slots 10. The doughnut-holder or foraminous retainer 8 is adapted to be moved from full-line position (Fig. 2) to dotted line position. When in full-line or lower position, said retainer is received within the kettle or caldron 13, which said kettle contains the lard or grease 65 in which the doughnuts are cooked, and is adapted to be heated by the fire 14. The locking dogs 11 are notched or rabbeted at 15 and the handles 9 seat in said notches 15 when the foraminous retainer is elevated to 70 dotted line position—that being the position in which the dough-nuts are allowed to drain and dry after completion of the cooking operation. Heretofore it has been customary to cook the doughnuts, and then to 75 set the receptacle in which they are retained upon the floor or a table to cool. The odors, smoke, and vapor would thus be disseminated throughout the room, but by this invention the doughnuts can be cooled and 80 drained as necessary, and yet the smoke and vapors are all carried up the flue. In this invention, however, after the doughnuts are cooked, the retainer 8, which, of course, is filled with doughnuts, is lifted from full line 85 to dotted line position (Fig. 2). The grease that drips from the cooked batch will fall into the caldron 13 and waste thereof is prevented. Moreover, when the retainer 8 is in elevated position, at least part of said 90 retainer is higher than the aperture 7 which is cut in the wall of said chamber 6; hence, when the retainer is elevated, a current of air will enter said aperture 7 and pass upwardly past the doughnuts contained therein, and this current of air will pass out through the exit 5 in the top of the hood 4, which exit is connected suitably to a chimney or flue. The doughnuts therefore, after 95 being cooked, thus dry and drain while suspended in a current of air, and hence do not become soggy or sour as is often the case where they are simply allowed to stand upon a table in non-circulating air.

This invention, it will be obvious, keeps 105 the drying doughnuts covered over and free from dirt and dust, holds them in a current of air, and prevents escape of the grease-

laden air or the unpleasant vapors into the room, and in these three features, among others, secures a distinct improvement in this art.

5 I claim as my invention:

1. A device of the character described comprising a hood, means for conducting the gases from said hood, a chamber beneath said hood, a foraminous retainer, the wall of 10 said chamber being apertured to permit passage therethrough of said retainer, and means for suspending said retainer within said chamber.

15 2. A device of the character described comprising a hood, means for conducting the gases from said hood, a chamber beneath said hood, a foraminous retainer, the wall of said chamber being apertured to permit passage 20 therethrough of said retainer, a handle for said retainer, and means secured to the wall of said chamber and adapted to engage said handle, thereby to suspend the retainer within said chamber.

25 3. A device of the character described comprising a hood, means for conducting the gases from said hood, a chamber beneath said hood, a foraminous retainer, the wall of said chamber being apertured to permit passage 30 therethrough of said retainer, a handle for said retainer, the wall of said chamber being slotted to receive said handle, and a locking member upon the wall of said chamber adapted to engage said handle and

thereby suspend the retainer in elevated position.

4. A device of the character described comprising a conical hood, means adapted to provide an exit therefrom through which the gases are adapted to pass, a foraminous retainer, a chamber beneath said hood within which said retainer is received, the wall of said chamber being apertured, and means for suspending said retainer within said chamber, the top edge of said retainer being higher than said aperture.

45 5. A device of the character described comprising a conical hood, means adapted to provide an exit therefrom through which the gases are adapted to pass, a foraminous retainer, a chamber beneath said hood within which said retainer is received, the wall of said chamber being apertured, a handle for said retainer, the wall of said chamber being slotted to receive said handle, and locking means adapted to engage said handle and suspend the retainer within said chamber, said locking means being placed 50 at a point whereby said locking means are adapted to retain said retainer higher than said aperture.

In testimony whereof I hereunto affix my signature in the presence of two witnesses.

GEORG MAYER.
